UNITED STATES PATENT OFFICE.

MARCUS B. BEHRMAN, OF NEW YORK, N. Y., ASSIGNOR TO AMERICAN SAFETY RAZOR CORPORATION, OF BROOKLYN, NEW YORK, A CORPORATION OF VIRGINIA.

SHAVING-STICK PACKAGE.

1,379,674.

Specification of Letters Patent. Patented May 31, 1921.

Application filed July 31, 1920. Serial No. 400,530.

To all whom it may concern:

Be it known that I, MARCUS B. BEHRMAN, a citizen of the United States, and a resident of New York city, in the county of New York 5 and State of New York, have invented certain new and useful Improvements in Shaving-Stick Packages, of which the following is a specification.

The invention relates to a package comprising a container or box, a stick of shaving soap to be inclosed therein and a holder of special construction applied upon the butt end of said stick and adapted when the stick is inserted into said container to 15 serve as a stopper for the same and as means for suspending the stick therein.

The object of the invention is to provide a holder for the stick of soap which will receive and cling to the butt end of the stick 20 and serve as a convenient handle for the stick, as a base for supporting the stick in an upright position upon a shelf or the like and as means for suspending the stick in its box or container and effectually sealing 25 said box or container. The holder of my invention is made in one integral piece of yielding or elastic material, preferably molded rubber, and of cup form to receive and cling to the end portion of the stick, 30 said holder having a base and a skirt portion, and said skirt portion being yieldable to fit and hug the stick and also to enter the mouth of the box or container and seal the same. The box or container has around its 35 mouth portion an annular beading which affords an interior annular groove, and the skirt portion of the holder has an annular beading adapted to enter said groove when the stick is inserted into said box, whereby 40 there becomes an interlocking engagement of the holder and box which serves to correctly position the holder and stick and insure the proper sealing of the box.

The invention will be fully understood 45 from the detailed description hereinafter presented, reference being had to the accompanying drawings, in which:

Figure 1 is a side elevation of a shaving soap package embodying my invention; 50 Fig. 2 is a vertical section through the same taken on the dotted line 2-2 of Fig. 3, and

Fig. 3 is a top view of the same.

In the drawings 10 designates a cylindrical tin box or container, 11 the stick of shaving soap and 12 the holder applied on

the butt end of said stick. The stick 11 is of the usual cylindrical form and not modified by the application of my invention thereto, and said stick 11 is provided with 60 the usual wrapping of foil on the like 13.

The box or container 10 has about its mouth an annular beading 14 which affords an annular interior groove 15, and in other respects the box 10 is of usual construction. 65 The purpose of the groove 15 will appear hereinafter.

The holder 12 is molded in one integral piece of reasonably soft or yieldable rubber or rubber-composition and comprises a base 70 portion 16 and a skirt portion 17 and they together form a cup which tightly receives and clings to the butt end of the stick 11. The holder 12 is generally of substantial thickness, and the central portion of the 75 base 16 of the holder is made thin or of diaphragm character, as at 18, so that when the stick is worn down the user may by pressing his thumb against the diaphragm 18 cause the remaining end of the stick to 80 project out from the holder preparatory to the removal of the same therefrom. The skirt portion 17 is adapted to closely enter the mouth of the box 10 and is formed with an annular beading 19 which on the 85 application of the holder to the box will first become compressed and then expand into the groove 15 thereof, whereby the holder and box become interlocked and the holder is assured a correct position and enabled to properly seal the box and also suspend the stick 11 therein. The skirt portion 17 is also formed above the beading 19 with an annular shoulder 20, which is adjacent to the upper edge of the box and with said 90 edge prevents the holder from being pushed to an undue extent into the box. 95

The holder 12 serves to suspend the stick 11 within and seal the box 10, as shown in Fig. 2, and said holder is to be employed 100 as a handle for withdrawing the stick from the box for use, the force required for withdrawing the holder from the box being sufficient to overcome the friction-fit of the holder in the box and the releasing of the 105 beading 19 from the groove 15. After the stick of soap has been withdrawn from the box, the holder 12 serves as a handle therefor and also as a base for supporting the stick in upright position upon a shelf or the like. The holder 12 being of elastic or rubber-like material will at all times cling 110

to the stick and serve as an effectual stopper for the box, and in addition when the holder is placed on a shelf or the like it will have no tendency to mar the same, nor will the holder become injured should it be knocked against a hard substance,—as, for illustration, a marble washstand.

What I claim as my invention and desire to secure by Letters-Patent, is—

10 1. A package for a stick of shaving soap comprising a container to inclose the stick and a cup-like holder of elastic material fitting upon the butt end of said stick and serving as a handle for the stick and a 15 stopper for said container while suspending the stick therein.

20 2. A package for a stick of shaving soap comprising a container to inclose the stick and an elastic cup-shaped holder fitting upon the butt end of said stick and serving as a handle for the stick and a stopper for said box, said holder comprising a base portion and a skirt portion and said base portion having a central thin depressible part 25 against which a thumb may be pressed for moving the butt end of the stick outwardly from said holder.

30 3. A package for a stick of shaving soap comprising a container to inclose the stick and an elastic cup-shaped holder fitting upon and clinging to the butt end of said stick and serving as a handle for the stick and a stopper for the container, said holder comprising a base portion and a skirt por-

tion, and said container about its mouth and 35 said skirt portion having respectively an interlocking annular groove and a beading for assuring the position of said holder within the mouth of said container.

4. A package for a stick of shaving soap 40 comprising a container to inclose the stick and an elastic cup-shaped holder fitting upon and clinging to the butt end of said stick and serving as a handle for the stick and a stopper for the container, said holder 45 comprising a base portion and a skirt portion, and said container having about its mouth an annular groove and said skirt portion having an annular beading to interlock with said groove and also a shoulder 50 above said beading to engage the edge of the container and prevent the holder from being pushed unduly into the container.

5. A package for a stick of shaving soap 55 comprising a container to inclose the stick and a cup-shaped holder fitting upon the butt end of the stick and comprising a base portion for supporting the stick in an upright position on a shelf or the like and to serve as a handle for the stick and a skirt 60 portion of elastic material adapted to cling to and thereby hold the stick and also serving as a stopper to engage the walls of the container about the mouth thereof.

Signed at New York city, in the county 65 of New York and State of New York, this 28th day of July, A. D. 1920.

MARCUS B. BEHRMAN.
